UNITED STATES PATENT OFFICE.

WALTER S. ADAMS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

CAR-TRUCK.

1,157,971.

Specification of Letters Patent. Patented Oct. 26, 1915.

Application filed November 17, 1914. Serial No. 872,509.

To all whom it may concern:

Be it known that I, WALTER S. ADAMS, a citizen of the United States, and a resident of the city of Philadelphia, county of Philadelphia, and State of Pennsylvania, have invented certain new and useful Improvements in Car-Trucks, of which the following is a specification.

My invention relates to a bolster support means in car trucks wherein the bolster is supported near its ends on a combination of leaf and coil springs, this combination allowing the bolster to be carried true without undue jar or vibration.

15 The present invention also resides in certain novel features of construction and combination of elements, which will be herein-after described and further pointed out in the claims appended hereto.

20 For a more particular description of my invention, reference is to be had to the accompanying drawings, in which—

Figure 1 is a side elevation of my improved bolster supporting arrangement with portions of the truck being shown to illustrate its application to the truck; Fig. 2 is a front elevation of the same; Fig. 3 is a sectional view of one end of the elliptic springs, showing the coil springs interposed between said elliptic springs; Fig. 4 is a side elevation, partly in section, of a modified form of bolster supporting means; Fig. 5 is a sectional view on the line 5—5 of Fig. 4, looking in the direction of the arrows; Fig. 6 is a plan view of the spring seats for supporting the coil springs, as shown in Figs. 4 and 5; Fig. 7 is another modified form of bolster supporting means; and Fig. 8 is a front elevation, partly in section, of the bolster supporting device shown in Fig. 7.

As my invention may be applied to many kinds of trucks, I do not attempt to show any one in particular, but disclose a portion 45 of a truck which may be taken as typical of a number and I show no parts that are irrelevant to my improvements. I do show portions of a frame 1, comprising top chords 2, transoms 3, gusset plates 4, bolts 5, 50 and reinforces 6, all of which may be of the conventional form.

The bolster 7 is mounted between the transoms 3, and gusset plates 4, by means of suitable bearing blocks 8 which carry spin-

dles 9 and other parts to be described below. 55 These bearing blocks 8 are fixed in place on the gusset plates 4 by bolts 10. Suspended from the spindles 9 are hangers 11. At the lower end of these hangers are carried spindles 12, which connect their lower ends, one 60 spindle connecting two hangers. Each spindle 12 is made square or of like cross section at its outer ends so as to fit corresponding parts of the hangers 11 and not turn therein. Between the hangers, however, the 65 spindle 12 is made circular in cross section so as to receive and support a suitable bearing in a bracket 13, which is fixed by means of bolts 14 to a spring seat 15 and to angle bars 16 by rivets 17; the parts 13, 14, 15, 70 16 and 17 forming a spring plank. The seats 15 hold the bands 18 of lower leaf springs 19. The bolster 7 is mounted on upper leaf springs 20, held together by bands 21. Between the ends of the upper leaf springs 20 and lower leaf springs 19 are coil springs 22 and 23, one surrounded by the other, and arranged within the inner spring 23, is a block 24 having shoulders 25 and projections 26 extending through perforations 27 in the leaf springs. 75

When a predetermined weight, or number of passengers is on the car, the coil springs 22 and 23 compress sufficiently to allow the leaf springs 19 and 20 to rest on the shoulders 25 of the block 24, and the leaf springs thereupon carrying any additional load imposed upon the car. 80

In the embodiment of my invention shown in Figs. 4, 5 and 6, there are spring seats 28, with springs 29 extending between them, between the ends of the leaf springs 19 and 20. Each of the spring seats is provided with a projection 30, said projections being preferably set at an angle to accommodate 90 the curve of the leaf springs and a surface, 30^a, said surface being preferably curved as shown. To accommodate the four leaf springs as shown herein, and to assist in uniting the same, each spring seat is preferably made in a single piece and each is provided with walls 31 for the reception of the springs 29. 95

In the further embodiment of my invention, as shown in Figs. 7 and 8, the leaf spring 20 is bent upwardly at 32 and the leaf spring 19 downwardly in like manner. Extending between the two widened por- 100

tions 33 thus formed are springs 34, carried by spring seats 35, each of said seats having projections 36, fitting perforations 37 in the leaf springs. This embodiment of my invention is not claimed in this application but is covered by my co-pending application, Ser. No. 19,448, filed April 6th, 1915.

In the embodiment shown in Figs. 4, 5 and 6, the spring caps 28 come together when a certain weight is imposed upon the car and then the balance of the weight is carried by the leaf springs 19 and 20. In the embodiment shown in Figs. 7 and 8 the portions 32 of the leaf springs come together and the balance of the load is then carried by the leaf springs.

Referring to the structure shown in Figs. 1 to 3, it will be noted that when the coil springs 24 and 23 are compressed, the leaf springs bear against and are supported on the inner ends 25^a of the shoulders 25 of the block 24. When thus supported, the operative length of the leaf springs is lessened and they thus become stronger and their resistance to the weight of the load is increased. In the structure shown in Figs. 4, 5 and 6 the same result is obtained when the leaf springs rest upon the surfaces 30^a of the spring seats 28. In the structure shown in Figs. 7 and 8 this result is obtained when the points 32 come together.

While I have shown and described one embodiment of my invention, it is obvious that it is not restricted thereto but is broad enough to cover all structures that come within the scope of the annexed claims.

What I claim is:

1. In a truck of the class described, a truck frame, a bolster mounted in said frame, leaf springs supporting said bolster, coil springs mounted between said leaf springs and cups for said coiled springs adapted to rest together when the coiled springs are sufficiently compressed.

2. In a truck of the class described, a truck frame, hangers supported by said truck frame, transversely disposed leaf springs supported by said hangers, a bolster supported by said leaf springs, coil springs mounted between said leaf springs and cups for said coiled springs adapted to rest together when the coiled springs are sufficiently compressed.

3. In a truck of the class described, a truck frame having hangers and means for supporting the same, a spring plank, carried by said hangers, leaf springs carried by said spring plank and supporting the bolster, coil springs mounted between said leaf springs and cups for said coiled springs adapted to rest together when the coiled springs are sufficiently compressed.

4. In a truck of the class described, a truck frame, a bolster mounted within said frame, leaf springs for supporting said

bolster, coil springs mounted between the ends of said leaf springs and cups for said coiled springs adapted to rest together when the coiled springs are sufficiently compressed.

5. In a truck of the class described, a truck frame, a bolster mounted within said frame, leaf springs for supporting said bolster, coil springs interposed between the leaf springs and a block for limiting the compression of said coil springs.

6. In a truck of the class described, a truck frame, a bolster mounted within said frame, leaf springs for supporting said bolster, perforations in said leaf springs, a block having projections adapted to enter the perforations in the leaf springs, springs interposed between the leaf springs and means on the block for limiting the compression of the coil springs.

7. In a truck of the class described, a truck frame, a bolster mounted within said frame, leaf springs for supporting said bolster, a block interposed between the leaf springs, shoulders on said block, projections on said block adapted to enter into perforations in the leaf springs and coil springs mounted between the leaf springs and surrounding the block.

8. In a truck of the class described, a truck frame, a bolster mounted within said frame, leaf springs for supporting the bolster, coil springs mounted between the leaf springs, a block mounted between the leaf springs and means on said block for limiting the movement of the ends of the leaf springs toward one another and shortening the operative length of the leaf springs when the limit of movement of the ends of the leaf springs toward one another has been reached.

9. In a truck of the class described, a truck frame, a bolster mounted within said frame, leaf springs for supporting said bolster, spring seats with curved edges adapted to abut mounted upon said leaf springs and coil springs supported by said spring seats.

10. In a truck of the class described, a truck frame, a bolster mounted within said frame, leaf springs supporting said bolster, spring seats, with projections thereon adapted to enter perforations in the leaf springs mounted at the ends of the leaf springs, coil springs supported by said spring seats between the leaf springs.

11. In a truck of the class described, a truck frame, a bolster mounted within said frame, leaf springs supporting said bolster, spring seats mounted at the ends of the leaf springs, projections on the spring seats at an angle to the same adapted to enter perforations in the leaf springs and coil springs arranged between the ends of the leaf springs and supported by the spring seats.

12. In a device of the class described, a truck frame, a bolster mounted within said

frame, leaf springs for supporting said bolster, the ends of said leaf springs being formed to provide space for the reception of cups, cups with surfaces adapted to abut 5 resting in the ends of said leaf springs and coil springs mounted in said cups.

13. In a truck of the class described, a truck frame, a bolster mounted within said frame, leaf springs for supporting said bolster, the ends of said springs being bent outwardly, spring seats mounted on the leaf 10 springs and coil springs mounted on the spring seats between the leaf springs.

14. A spring arrangement for vehicles, 15 comprising leaf springs, compression coil springs mounted between the ends of said

leaf springs and means for limiting the compression of said coil springs.

15. A spring arrangement for vehicles, comprising leaf springs, coil springs mounted between the ends of said leaf springs, a block interposed between the ends of the leaf 20 springs to limit the compression of the coil springs.

Signed at the city and county of Philadelphia, State of Pennsylvania, this 2nd day of November, 1914.

WALTER S. ADAMS.
